(57) **CLAIM**

The ornamental design for multimedia tracker, as shown and described.

DESCRIPTION

FIG. 1 is a front perspective view of a multimedia tracker device;

FIG. 2 is a front elevational view thereof;

FIG. 3 is a rear elevational view thereof;

FIG. 4 is a right side elevational view of thereof;

FIG. 5 is a left side elevational view thereof;

FIG. 6 is a top plan view thereof;

FIG. 7 is a bottom plan view thereof;

FIG. 8 is a front perspective view of another embodiment of a multimedia tracker device including a cap;

FIG. 9 is a front elevational view thereof;

FIG. 10 is a rear elevational view thereof;

FIG. 11 is a right side elevational view of thereof;

FIG. 12 is a left side elevational view thereof;

FIG. 13 is a top plan view thereof;

FIG. 14 is a bottom plan view thereof; and,

FIG. 15 is a front perspective view thereof with the cap removed and a user interface portion exposed.

Objects shown in broken lines are shown for environmental purposes only and form no part of the claimed design. Where applicable, the use of separation and bracket indicate that, for ease of illustration, the precise width or height of the designs not claimed.

1 Claim, 9 Drawing Sheets
